CLAIM

The ornamental design for a food brush handle, as shown and described.

DESCRIPTION

FIG. 1 is a front elevational view of a food brush handle, showing our new design;

FIG. 2 is a right-side elevational view thereof;

FIG. 3 is a rear-side elevational view thereof;

FIG. 4 is a left-side elevational view thereof;

FIG. 5 is a top plan view thereof;

FIG. 6 is a bottom plan view thereof; and,

FIG. 7 is a bottom perspective view thereof.

The broken lines show portions of the food brush handle and form no part of the claimed design.

1 Claim, 6 Drawing Sheets
